United States Patent Office.

WILLIAM O. HARRISON, OF CHITTENDEN, VERMONT.

Letters Patent No. 80,170, dated July 21, 1868.

IMPROVEMENT IN HARVESTERS.

The Schedule referred to in these Letters Patent and making part of the same.

TO ALL WHOM IT MAY CONCERN:

Be it known that I, WILLIAM O. HARRISON, of Chittenden, in the county of Rutland, and State of Vermont, have invented a new and improved Hedge-Trimmer, and Mowing and Reaping-Machine; and I do hereby declare that the following is a full, clear, and exact description thereof, which will enable those skilled in the art to make and use the same, reference being had to the accompanying drawings, forming part of this specification, in which—

Figure 1 represents a side elevation, partly in section, of my improved mowing-machine, the plane of section being indicated by the line $x\ x$, fig. 2.

Figure 2 is a plan or top view of the same.

Figure 3 is a detail under side view of the same.

Figure 4 is a detail vertical section of the same, taken on the plane of the line $y\ y$, fig. 2.

Similar letters of reference indicate corresponding parts.

A, in the drawing, represents the frame of a mowing or reaping-machine, supported by two driving-wheels, B and C, of which one is mounted, and the other hung on a horizontal shaft, D, as shown.

Upon the shaft D is also mounted a bevel or other gear-wheel, E, which meshes into the teeth of a pinion, a, that is fitted around an arbor, b, so that it can slide on the same.

In fig. 3, the arrangement of the pinion a and arbor b is best shown.

The arbor can revolve in its bearings, and has a shoulder, c, between which and the pinion a , a spiral spring, d, is arranged, which serves to press the pinion against a clutch, e, that is formed on the arbor b , as shown.

When the pinion is, by means of the clutch, locked together with the arbor, it will impart its own motion to the same, but when, by means of a lever, F, the pinion is drawn off the clutch, as in fig. 3, the arbor will remain stationary, although the pinion is revolved by means of the gear-wheel E.

On the arbor b is firmly fixed a suitable gear-wheel, G, which meshes into a pinion, f, that is mounted on or near the end of a shaft, H.

The shaft H has its bearing near one end of the frame A, which is opposite to where the cutter-bar is arranged in a block, g, that is hinged to the under side of the frame A, as shown in fig. 1.

The free end of the shaft H can thus be moved up or down at will, which can be done by means of a suitable lever, I, or other equivalent device, without bringing the pinions f and G out of gear.

The free end of the shaft H may also be supported in a block or blocks, h, which are attached to and project from a bar, i, which connects the blocks h and g .

The finger-bar J is hinged with one end to the free end of the shaft H, so that it can turn on the same, and can also be raised or lowered with the same by means of the lever G.

The finger-bar may be of ordinary or suitable construction.

Upon its face rests a cutter-bar, L, of suitable construction, carrying a slotted block, l, into which a crank-pin, m, projecting from a crank or wheel, n, mounted on the end of the shaft H, is fitted.

Thus the cutter-bar will, as the shaft H is revolved, receive reciprocating motion, and will work as easily in any position of the finger-bar, the strain on the connecting-rod being not at all experienced in this machine.

The finger-bar may be arranged in front or rear of the frame, and the connection of the shaft H with the gear-wheel E may be arranged in any other suitable manner, instead of that herein described.

The connection of the cutter-bar with the shaft H may be arranged otherwise than shown, with equal result.

I claim as new, and desire to secure by Letters Patent—

The arrangement of the gear-wheel G, constructed as described, hinged block g , extension i , bearing h , pinion f , and shaft H , pivoting the finger-bar to the machine, all constructed and operating as herein described.

WILLIAM O. HARRISON.
